UNITED STATES PATENT OFFICE.

WILLIAM HARRISON WHEELER, OF SCIOTOVILLE, OHIO.

TURN-TABLE FOR CRANES.

SPECIFICATION forming part of Letters Patent No. 398,867, dated March 5, 1889.

Application filed November 30, 1888. Serial No. 292,300. (No model.)

To all whom it may concern:

Be it known that I, WILLIAM HARRISON WHEELER, a citizen of the United States, residing at Sciotosville, in the county of Scioto 5 and State of Ohio, have invented a new and useful Improvement in Turn - Tables for Cranes, of which the following is a specification.

My invention relates to an improvement in 10 turn-tables for cranes; and it consists in the peculiar construction and combination of devices, that will be more fully set forth herein-after, and particularly pointed out in the claims.

15 In the accompanying drawings, Figure 1 is a side elevation of a crane embodying my improvements. Fig. 2 is a top plan view of the same. Fig. 3 is a front elevation. Fig. 4 is a sectional view taken on the line $x-x$ of Fig. 3.

20 A represents a pair of vertical standards, which are connected at their upper ends by a cross-beam, B, and are braced against forward inclination by a pair of inclined beams, C.

D represents a cross-beam, which also connects the standards A at a suitable distance below the beam B. A frame comprising two 25 pairs of standards, E, and cross-beams F, connecting their upper ends, and in the same horizontal plane with the beam D, is arranged in rear of the standards A, and the said beams

30 D and F are connected together by a pair of rearward-converging boards or joists, G, which are bolted thereon, as shown.

On the upper sides of the joists G, near their 35 rear ends, are blocks H, and on the said blocks are bars I, said blocks and bars being bolted to the joists G and the rear ends of said bars projecting rearward beyond the blocks H. Adjusting-openings K are made in the bars I 40 and in the joists, and in the said openings are fitted adjustable pins L, on which are journaled pulleys M.

N represents a pair of longitudinal beams, which are bolted on the beam D and on the forward beam, F, near the centers of said beams, and project forward beyond the beams E, as shown. Radial beams O are also bolted on the beam D and the foremost beam, F, and are arranged beyond the outer side of the beams 45 N, and also project beyond the front side of

beam D. A double platform, P, which is semi-circular in shape, is bolted on the upper and lower sides of the projecting ends of beams N O and let into the said beams, the outer edges of the upper and lower sides of the platform projecting beyond the ends of the radial beams and forming flanges R.

55 S represents a series of sheaves or pulleys arranged between the flanges R and journaled on bolts or pins T, that connect the upper and lower platforms.

U represents a pair of blocks arranged transversely between the beams N, at a suitable distance in advance of beams D, and having their ends bolted on the upper and lower 60 sides of said beams N. A central opening is made in the block U concentric with the semi-circular platform, and in the said opening is a pivotal bolt or pin, V.

65 W represents a frame comprising a pair of inclined upward-converging beams, X, and a plate or beam, Y, connecting their upper ends and arranged in the same vertical plane with and directly over the blocks U. A pair of inclined brace-bars, Z, have their upper ends 70 bolted to the ends of the plate or beam Y and are bolted near their lower ends to the standard Z. A pivotal pin, A', projects from the center of the plate or beam Y and forms the 75 fulcrum for a yoke, B'.

80 C' represents the boom, which has its lower ends pivoted on a suitable support arranged under the center of and below the platform, and has its upper outer end connected to the ends of the yoke B' by guy-chains D'.

85 E' represents a pair of parallel arms arranged on opposite sides of the boom bearing on the upper platform, P, and having their inner ends bolted to opposite sides of the block F', the said block being pivoted on the upper 90 end of the pin or bolt V. A similar pair of arms, G', are arranged under the lower platform, P, with their outer ends on opposite sides of the boom and their inner ends bolted to a block, H', which is in all respects similar 95 to block F', and is pivoted on the lower end of pin V, and the outer portions of the arms E' G' are connected together by vertical bars I'. Guy rods or chains K' connect the outer ends of arms E' with the ends of the yoke B'.

A chain, L', engages grooves in the pulleys M and S, and has its ends crossed and secured to the innermost pair of bars, I', the said chain being maintained at the requisite tension by 5 adjusting the bearing-pins L of the pulley M outward or inward in the openings N. Chains M' are attached to opposite sides of the endless chain L', and to suitable drums or other devices, (not shown,) by which either side of 10 the chain L' may be drawn rearward in such manner as to cause the arms E' and G' to be swung to the right or left, and thereby turn the boom to any desired position.

It will be understood from the foregoing description that the arms E' G', the boom, and the yoke are the only parts that turn, the turn-table platform P remaining stationary at all times.

A crane thus constructed is very cheap and 20 simple, and may be operated with a minimum expenditure of power.

In some cases it may be desirable to dispense with the lower arms, G', and to lengthen the upper arms, E', and this may be very 25 readily done.

Having thus described my invention, I claim—

1. The combination of the platform having the guiding-sheaves S, the boom, the pivoted 30 arms on the platform on opposite sides of the boom, and the operating-chains attached to the said arms and engaging the guiding-sheaves, whereby the boom may be swung to

any desired position, substantially as described.

2. The combination of the semicircular platform having the guiding-sheaves S arranged between its sides, the frame W, the yoke B', pivoted thereon, the pivoted boom, the guys connecting the upper end thereof to the ends of the yoke, the pivoted arms on the platform on opposite sides of the boom, the guys connecting the outer ends of said arms to the ends of the yoke, and the operating-chains engaging the guiding-sheaves and attached to 40 the pivoted arms, whereby the latter may be swung to move the boom in either direction, substantially as described.

3. The combination of the frame having the semicircular platform at one end provided with the guiding-sheaves and the adjustable tightening-sheaves N at the opposite end, the pivoted arm on the platform, the endless chain engaging sheaves N, and the sheaves in the platform and attached to the pivoted arms, 50 for the purpose set forth, and the boom arranged between the pivoted arms, substantially as described.

In testimony that I claim the foregoing as my own I have hereto affixed my signature in 55 presence of two witnesses.

WILLIAM HARRISON WHEELER.
